(57) **CLAIM**

The ornamental design for a shutter louver pin, as shown and described.

DESCRIPTION

FIG. 1 is a front elevated isometric view of the shutter louver pin;

FIG. 2 is a left side view of the shutter louver pin;

FIG. 3 is a right side view of the shutter louver pin;

FIG. 4 is a top view of the shutter louver pin;

FIG. 5 is a bottom view of the shutter louver pin;

FIG. 6 is a front view of the shutter louver pin;

FIG. 7 is a rear view of the shutter louver pin;

FIG. 8 is a front elevated isometric view of two shutter louver pins positioned in opposite ends of a louver for a shutter;

FIG. 9 is a front view of the shutter louver pins positioned in a louver for a shutter;

FIG. 10 is a rear view of the shutter louver pins positioned in a louver for a shutter;

FIG. 11 is a top view of the shutter louver pins positioned in a louver for a shutter, the bottom view being identical to the top view; and,

FIG. 12 is a fragmentary end view of the shutter louver pin positioned in one end of a louver for a shutter.

The shutter louver pin shown in broken line in FIGS. 8-11 form no part of the claimed design. Also, the shutter louver shown in broken line in FIGS. 8-12 forms no part of the claimed design. The shutter louver shown in FIGS. 8-11 is shown broken away in FIGS. 8-11 to indicate indeterminate length.
